Attnys.

UNITED STATES PATENT OFFICE

RALPH K. BECKER, OF CLEVELAND, OHIO, ASSIGNOR OF FORTY-FIVE ONE-HUNDREDTHS
TO BERT M. KENT, OF CLEVELAND, OHIO

CARTON

Application filed November 16, 1929. Serial No. 407,589.

This invention relates to cartons having pouring spouts formed therein and, more particularly, relates to certain improvements in the carton disclosed in my earlier application Ser. No. 387,612, filed August 22, 1929.

5 It is one of the objects of the invention to provide a carton of the usual rectangular shape, that is commonly used for packing granular or powdered materials, in which the pouring spout is formed within the limits of the ordinary blank that is now used to make a carton without a pouring spout, so that the provision of the pouring spout would not require the use of any additional material.

10 A further object of the invention is to provide a carton with a pouring spout which may be formed therein in connection with the operation of cutting out the blank for the carton so that no additional blanking operations are required.

15 A further object of the invention is to provide a carton with a pouring spout device that is so formed that the carton may be manufactured on the equipment that is now used for the manufacture of cartons, without pouring spouts, and which may be sealed by the usual sealing machines and not require any special equipment.

20 It is a further object of the invention to provide a carton having a pouring spout that will be devoid of externally projecting parts, that may be conveniently and quickly opened, and that may be readily closed and positively retained in the closed position.

25 Other objects of the invention and the features of novelty will be apparent from the following description taken in connection with the accompanying drawings, of which—

30 Fig. 1 is a perspective view of a portion of the carton, embodying my invention, the pouring spout being shown in the open position;

35 Fig. 2 is a perspective view of the carton, as it appears before the pouring spout device is opened;

40 Fig. 3 is a plan view of the blank for this carton;

45 Fig. 4 is a perspective view of the end of the carton, which contains the pouring spout

device, with the flaps about to be folded into the sealed arrangement;

50 Fig. 5 is a view similar to Fig. 4 but showing all but the outer flap, in the sealed arrangement; and

55 Fig. 6 is a view similar to Fig. 2 with a portion of the outer flap broken away to show the arrangement by which the pouring spout is locked in the closed position.

60 Referring to Fig. 3 of the drawings, the blank from which the carton is made is formed from paper stock, in the usual manner, by means of dies which score the blank along the lines 10, 11, 12, 13, 14 and 15, these score lines defining the sides 16, 17, 18 and 19, 65 of the carton. A sealing strip 20 is left along one edge of the side 16 and has the extensions 21 and 22 at its opposite ends. When the carton is assembled the strip 20 is glued to the inner surface of the side 19, along the edge 23, and the extensions 21 and 22 are glued to the inner surfaces of the flaps 24 and 25, respectively. One end of the carton is formed by the flaps 24, 26, 27 and 28, these flaps being 70 folded into overlapping arrangement and glued together in the usual manner. The opposite end of the carton is formed by the flaps 25, 29, 30 and 31, but these flaps are especially formed to provide the pouring spout device 75 which will now be described.

80 The flap 30 is formed with a tongue 32 which is creased along the lines 33 and 34 and cut along the lines 35, these cuts ending at the points 36. The crease lines 33 and 34 permit the tongue 32 to be folded into U-shape, as 85 shown in Fig. 1.

85 The flap 29 is formed with a U-shaped opening 7 which forms a tongue 38 and when the carton is assembled the opening 37 is arranged over the tongue 32 and the tongue 38 is glued to the tongue 32 so as to act as a reinforcement for the latter. The flap 29 is also provided with an opening 39 which is separated from the opening 37 by the bridge-like portion 40, which will be hereinafter referred 90 to.

95 The flap 25 is provided with the cut lines 41 and the flap 31 is provided with lines of perforations 42, 43, 44 and 45, arranged as shown. Within the portion bounded by the

lines 42, 43, 44 and 45, there is a U-shaped cut or perforated line 46 which forms a tongue 47 that is adapted to be secured on the tongue 38. The flap 31 is also provided with a cut line 48, arranged at right-angles to and meeting the line 45.

The manner of folding the flaps 25, 29, 30 and 31, in order to seal one end of the carton and form the pouring spout therein, will be apparent from Figs. 4 and 5. The flap 25 is first folded to the position shown and then the flap 30 is folded in so that the end of the tongue 32 will overlie the end portion of the flap 25. The flap 29 is provided with glue on its inner and outer surfaces and is then folded down on the flaps 25 and 30 so that the tongue 38 will be secured on the tongue 32 as shown in Fig. 5. The flap 31 is then folded over the flap 29 and glued thereto, the tongue 47 being thus secured on the tongue 38. By these operations the end of the carton will then be entirely sealed, as shown in Fig. 2.

The various cut lines and openings in the different flaps are so arranged that, when the flaps are in their sealed arrangement, the lines 45 and 48 will be over the opening 39 and the bridge-like portion 40 will be secured to the inner surface of the section 49, of the flap 31.

The opening 39 and the cut 48 permits the portions of the flap 31, lying on opposite sides of the line 48, to be depressed so as to enable one to insert the finger nail or a tool under the edge of the section 49, that is formed by the line 45. The section 49 may then be torn out, thereby leaving the tongue 47 attached to the tongue 38. The end 50 of the pouring spout will then be accessible and the spout may be withdrawn through the opening formed by the removal of the section 49 and, as the spout is withdrawn, the longitudinal edges of this opening will automatically fold the spout as shown in Fig. 1 and, in this condition, it may be used for pouring out the contents of the carton. When it is desired to close the spout, it is pushed back to its initial position and, as it returns, the edges of the tongue 32, which form the sides 51 of the spout, will engage in the cuts 41, as shown in Fig. 6, and thus hold the spout in its closed position. The cuts 41 also increase the flexibility of the portion of the flap 25 which underlies the tongue 32 and thus facilitate the withdrawal of the spout. Since the removable section 49 will, in sealing the end of the carton, be glued to the bridge 40 this removable section will be firmly supported and, at the same time, thoroughly secured in its position. In removing the section 49, it may take the bridge 40 with it or the gluing may break but, in either case, the removal of the section 40 is very simple.

Having thus described my invention, what I claim is:

1. A carton having a wall comprising three

overlapping flaps, the inner one of said flaps being formed with a foldable spout-forming section, the intermediate and outer flaps having tongues which are secured to said spout-forming section, and the outer flap having a tear-out section which is removable independently of said tongues and which upon being removed provides an opening in said outer flap through which said spout-forming section is accessible.

2. A carton having a wall comprising four flaps, the two innermost of said flaps being attached to opposite walls of the carton and having their ends in overlapping arrangement, one of said two flaps being formed with a foldable spout-forming section and the other of said two flaps being cut on opposite sides of the portion thereof which underlies said spout-forming section to increase the flexibility of said underlying portion and hold the spout-forming section in its closed position, and the other two of said flaps being arranged in overlapping relation on said two innermost flaps and having registering openings through which said spout-forming section may be withdrawn.

3. A carton having a wall comprising four flaps, the two innermost of said flaps being attached to opposite walls of the carton and having their ends in overlapping arrangement, one of said two flaps being formed with a foldable spout-forming section and the other of said two flaps being cut on opposite sides of the portion thereof which underlies said spout-forming section to increase the flexibility of said underlying portion and hold the spout-forming section in its closed position, and the other two of said flaps being arranged in overlapping relation on said two innermost flaps, the inner one of said other two flaps being cut out to provide openings over the side portions of said spout-forming section and to form a tongue which is secured to the latter, and the outermost of said flaps having a removable section to provide an opening through which said spout-forming section may be withdrawn and said opening being so shaped and arranged that the spout-forming section is automatically folded into a U-shaped spout in being withdrawn therethrough.

4. A carton having a wall comprising four flaps, the two innermost of said flaps being attached to opposite walls of the carton and having their ends in overlapping arrangement, one of said two flaps being formed with a foldable spout-forming section and the other of said two flaps being cut on opposite sides of the portion thereof which underlies said spout-forming section to increase the flexibility of said underlying portion and hold the spout-forming section in its closed position, and the other two of said flaps being arranged in overlapping relation on said two innermost flaps, the inner one of said other

two flaps being cut out to provide openings over the side portions of said spout-forming section and to form a tongue which is secured to the latter, and the outermost of said flaps 5 having a tongue that is secured on the first-mentioned tongue, and a removable section to provide an opening through which said spout-forming section may be withdrawn and said opening being so shaped and arranged that 10 the spout-forming section is automatically folded into a U-shaped spout in being withdrawn therethrough.

5. A carton having a wall comprising three overlapping flaps, the inner of said flaps having formed therein a spout-forming section, the intermediate flap being provided with two openings one of which is over said spout-forming section, and the outermost of said flaps having a cut line over the other of said 20 openings and a removable section to provide an opening through which said spout-forming section may be withdrawn.

6. A carton having a wall comprising three overlapping flaps, the inner of said flaps 25 having formed therein a spout-forming section, the intermediate flap being provided with two spaced openings one of which is over said spout-forming section, and the outermost flap having a removable section 30 to provide an opening through which said spout-forming section may be withdrawn, said removable section being secured to the portion of said intermediate flap which lies between said openings.

35 7. A carton having a wall comprising three overlapping flaps, the inner of said flaps having formed therein a spout-forming section, the intermediate flap being provided with two spaced openings one of which is over 40 said spout-forming section, and the outermost flap having a removable section to provide an opening through which said spout-forming section may be withdrawn, said removable section being secured to the portion 45 of said intermediate flap which lies between said openings, and said intermediate and outermost flaps having overlapping tongues which are secured to said spout-forming section.

50 8. A carton having a wall comprising three overlapping flaps, the inner of said flaps having formed therein a spout-forming section, the intermediate flap being provided with two spaced openings one of which is over 55 said spout-forming section, and the outermost flap having a removable section to provide an opening through which said spout-forming section may be withdrawn and also having means formed therein at one side 60 of said removable section and over the other of said openings whereby the edge of said removable section is rendered accessible.

9. A carton having a wall comprising three overlapping flaps, the inner of said flaps having formed therein a spout-forming section,

the intermediate flap being provided with two spaced openings one of which is over 70 said spout-forming section, and the outermost flap having a removable section to provide an opening through which said spout-forming section may be withdrawn and also having means formed therein at one side of said removable section and over the other of said openings whereby the edge of said removable section is rendered accessible, and 75 said removable section being secured to the portion of said intermediate section which lies between said openings.

In testimony whereof, I hereunto affix my signature.
